COMBINED CHAIR AND COLLAPSIBLE TRAY UNIT

Don Ray Gill, Hammond, Ind., assignor to Mohasco Industries, Inc., Amsterdam, N.Y.

Filed June 23, 1971, Ser. No. 156,157

Term of patent 14 years

Int. Cl. D6—02

U.S. Cl. D6—42

FIG. 1.

FIG. 2.

FIG. 3.

FIG. 1 is a front perspective view of a combined chair and collapsible tray unit showing my new design with the collapsible tray unit in raised position.

FIG. 2 is a front perspective view similar to FIG. 1 but showing the tray in closed position.

FIG. 3 is a front perspective view of the combined chair and collapsible tray unit showing the side not illustrated in FIG. 2.

The back of the chair is conventionally plain.

I claim:

The ornamental design for a combined chair and collapsible tray unit, as shown and described.
